THE NORRIS PETERS CO. PHOTO-LITHO, WASHINGTON, D. C.

UNITED STATES PATENT OFFICE.

NEWTON L. COLLAMER AND WILLIAM F. MAHONY, OF WASHINGTON, DISTRICT OF COLUMBIA, ASSIGNORS TO SAID NEWTON L. COLLAMER, OF WASHINGTON, DISTRICT OF COLUMBIA.

DESIGNATOR OR ENUMERATOR.

SPECIFICATION forming part of Letters Patent No. 694,730, dated March 4, 1902.

Application filed November 14, 1901. Serial No. 82,817. (No model.)

To all whom it may concern:

Be it known that we, NEWTON L. COLLAMER and WILLIAM F. MAHONY, citizens of the United States, residing at Washington, District of Columbia, have invented certain new and useful Improvements in Designators or Enumerators; and we do hereby declare the following to be a full, clear, and exact description of the invention, such as will enable others skilled in the art to which it app pertains to make and use the same.

The present invention is a device for designating certain conditions, respectively, relative to names in a series, to which end it is a designator as explained herein, and in the practical application of this idea at present the names are the titles of articles, while the designations are numerals, and therefore the device when so used is an enumerator in that it respectively indicates the number of each article.

Broadly speaking, the present invention consists in a body having series of notches along opposed edges, names printed adjacent the notches in one series, designations printed adjacent the notches of another series, and an indicator leading from a name-notch to a designation-notch; and specifically the invention consists in the various means for carrying out this general idea. In connection with the above, an important feature which may be used is a fastening device for holding the indicator (if the latter be a cord, which it usually is) after the same has been wound about the body to produce several designations, and specifically this fastening device is by preference a series of slits formed in the edge of the body and into which the cord may be drawn. These details are susceptible of modifications, some of which are shown, and the entire device may be amplified to a considerable extent, as will be understood.

Heretofore devices for attaining substantially the same end have been constructed in a variety of ways, of which two only need be mentioned in order to point the difference between them and the present invention. One is a body with a series of names printed upon it and opposite them a horizontal row of holes arranged in vertical lines, each of

which latter is numbered, and pegs or plugs are inserted in the holes to designate or indicate the proper number of the article opposite which each peg stands. The other is a card or tablet having a series of names along one edge and opposite the same rows of perforations arranged in vertical lines numbered at their upper ends, and a marker, such as a cord, is laced or rove through certain of the perforations to designate or indicate as do the plugs in the instance above. The present invention differs from these devices in that it has no pegs to become lost and it requires no sewing or lacing of a cord. On the contrary, it can be very quickly manipulated to perform its desired work.

In the accompanying drawings, which illustrate the broad idea in one of its many applications and only a few of the modifications and amplifications of which it is susceptible, Figure I is a plan view of the designator in its preferred form and used as a laundry-counter. Fig. II is a fragmentary view showing several forms of notches. Fig. III is a similar view showing several forms of fastening devices. Fig. IV is a plan view showing how more than two series of notches could be employed. Fig. V illustrates one modification which may be given the shape of the body. Fig. VI is a perspective view illustrating how the body might be solid—here a cube. Fig. VII is a plan view of the four active sides of the cube laid out so as to show its operation. Fig. VIII shows a modification of the indicator, here illustrating two forms of elastic cords which might be employed. Fig. IX is a perspective view illustrating how the body might be reinforced at some or all of its edges. Fig. X is a plan view showing the use of a plurality of indicators of different color. Fig. XI is an edge view of one form of metallic body.

Referring to the drawings, 1 is the body, which is by preference a piece of cardboard of the requisite size, shape, and stiffness. By preference it is rectangular and oblong, as best seen in Fig. I, although it could be square, diamond shape, oval, or of any other suitable shape, Fig. V illustrating the body as round in contour. It is only necessary that in the simplest form of the invention

there be at least two edges which are opposed to each other. In Fig. I these are the side edges, in Fig. IV the lower end is also employed, and in Fig. V four opposed edges are shown, as will be described. Along the opposed edges are formed notches 2, which may be of any of many shapes, several being shown in Fig. II. It is only necessary that these notches be distinct, sufficiently deep, 10 and by preference equidistant, so as to facilitate printing adjacent to them, and by preference the notches are formed by cutting the card with a corrugated or an angular-shaped knife-edge, as shown near the top of Fig. II. 15 Along another opposed edge are formed other notches, which may be similar to the first set in shape or not. By preference they are the same in shape and spacing and for the same reason. Adjacent one edge is printed a series 20 of pictures, characters, or words constituting names, as shown at 3 in Fig. I, and adjacent the opposed edge is printed a series of pictures, characters, words, letters, or numerals constituting designations 4, as shown 25 at the right edge of this view. The names may be names of persons or of articles, and, in fact, by the term "names" is intended to be included anything which can be arranged in one series or in more than one series along 30 this edge. The designations are by preference numerals, such as abstract numbers, as shown in Fig. I, or concrete numbers—that is to say, the designations 4 might be arranged in one series or in a plurality of series, such as pounds 35 and ounces, then dozens, then pints and quarts. It is even possible that the designations may be other than numerals, to which end the term "designations" is intended to convey any condition relatively to the names which 40 it may be desired to indicate. As an illustration, the names might be names of people and the designations might be names of cities to which those people had been sent, or both names and designations might be proper 45 names and the indicator to be described below would connect the names in one series with the names in the other and designate that the two persons mentioned had been paired off for some reason of which it was de- 50 sired to make note.

5 designates the indicator, which in the preferred form of the invention is a piece of cord attached at some suitable point to the body 1. In Fig. I it is attached to an eyelet 6 at 55 the top of the card, by which the latter is hung up; but it is clear that the indicator could be attached at one end to the card in any other manner. It would be within the scope of this invention, if a permanent record were to be 60 made, to use a line, as of ink or pencil, for the indicator, or anything else that would lead from one of the names to one of the designations. In Fig. VIII the indicator 51 is an elastic cord and the indicator 52 is an elastic 65 band leading completely around the body 1, and therefore avoiding the necessity for any independent fastening, as at 6 or elsewhere,

since its own body at the rear of the card serves as such fastening.

In Fig. X there are two indicators 53 and 54, and this view illustrates how a plurality of indicators of different color could be used simultaneously on the same card, one of which, for instance, to designate a gentlemen's wash and the other ladies' wash. With the simplest form of indicator, which is a piece of tape, cord, or string, after it has been wound around the card to produce the proper designations, some provision must be made to fasten the free end in order to prevent the indicator from uncoiling or unwinding by its own weight, and thus undoing the work of designation. Without limiting the invention to the use of any special form of fastening means, the simplest form is probably a series of slits 10 cut in one end of the card, as indicated in Fig. I. Other forms are shown in Fig. III with the cord indicator 5 wound around to engage with some of them. At the bottom of this view is illustrated an eyelet 101, and the cord indicator could be strung through that eyelet and allowed to hang or could be tied into the eyelet with a bow-knot. Of course the fastening means could comprise something attached to the face of the body 95 or driven into it; but it is preferred to retain the simplicity of parts as far as possible.

In Fig. IV is illustrated how there might be three sets of notches 2, and herein they are shown along each side edge and also along the lower end. In the bottom of one of said notches in the lower end in this view is cut a slit 105, which illustrates how this or any other notch could be continued into a fastening device, and thus serve a double function. 105 In Fig. V are illustrated four sets of notches 2. In Figs. VI and VII is illustrated a cube or square stick, whereof the two faces 102 and 103 are marked adjacent their opposite corners with names and designations and the two remaining faces are blank. These faces may be reserved for the advertising matter 15, which may occur where indicated in Fig. I and elsewhere throughout the various views, provided it does not conflict with the matter 115 necessarily printed upon the body. In the common practice at the present time these devices are made in great numbers with a merchant's advertisement upon them, as at 17, and are given away, as is well understood. 120 At 16 in Fig. I may be printed directions for using the device, which may also be printed upon any form.

Printing has been spoken of. It is clear that the marks upon the body could be made 125 in any other way, and it is within the scope of the invention to print or otherwise form such marks as are permanent and to leave some or all of the names and designations blank, as by making the body of celluloid or 130 slate, to permit writing thereon and erasing therefrom. Instances may occur where a plurality of designations are desirable in connection with one name, as shown in Fig. IV.

- By preference the indicator is led last to the fastening device, and the latter may be in such form as to itself constitute a designation, as shown at the top of Fig. I, or, if preferred, the mouth of the slit may be enlarged, as shown at 105 in Fig. IV, so that the device becomes a combination designation-notch and fastening means, and possibly the slits shown at the top of this view could be then omitted. In Fig. IX the edges of the card are stiffened by bent metal clamps 20, which themselves carry the notches 2, while the card is plain. This view also illustrates how an additional strip 21 of paper or card might be inserted beneath the clamp 20 so as to change the designations and how a similar strip could be used adjacent the other edge so as to change the names, all of which comes within the scope of this invention.
- The use of this invention in the form completely illustrated on the drawings, which is that of a laundry-card, is as follows: The card is grasped at the top by the left hand, and the indicator is led from its point of fastening, thence behind the card, and through a left-hand notch 2 opposite a name-word 3. In Fig. I it leads first through the notch "Nightshirt." The cord 5 is then carried across the face of the card 1 and through a right-hand notch opposite the proper designation. In Fig. I it passes through the notch opposite "3," which indicates that three night-shirts have been sent to the wash. The cord is then wound in a similar manner all the way down the card. In Fig. I it is led next to "Shirts" and then across to "5" to indicate that five shirts have gone to the wash, and so on. Finally, the cord is led to the fastening device, if it be employed. In Fig. I it would be led from the notch opposite "8" obliquely upward and drawn tightly into a slit 10 opposite the day of the week on which the wash is expected to be returned. As shown in Fig. I, a row of price-numerals 39 is placed opposite the words 3, and in this use of the device these are the prices, respectively, which the laundryman charges for washing the various articles. It is obvious that these prices are entirely separate and distinct from the abstract numerals 4, and it is clear that such prices or other data could be employed in conjunction with the name-words if the use of the article made it advisable. In Fig. IV between the designation of the number of various garments that are sent and the designation of the day of the return the cord passes through an intermediate series 40 of designations, which in this case are notches 2 in the lower end of the card opposite any printed matter desired, in the present instance being words relative to the nature of payment. In Fig. V the cord starts at 60, passes behind the body, connects the names 31 with the designations 41, then passes again behind the body and connects the names 32 with the designations 42, and then returns to the point 33 to repeat the operation. Thus it will be seen that a plurality of series of designations may be accomplished on a single card by a single indicator. 70 In Figs. VI and VII one system of designations may occur on the face 102 and another system on the face 103, the indicator where it passes across the faces 15 designating nothing. In Fig. VIII one indicator 52 may remain on the card, while the other one, 51, may be changed at will. In Fig. X two systems of designations may be effected on the same card by two indicators of different color.
- Fig. IX opens a field for modifications not necessary to describe in detail. It is clear that the clamps could be permanently secured upon a single body of cardboard or other delicate material, and if the strips 21 are to be inserted the clamps 20 must be capable of receiving two thicknesses. It would be possible to make the entire body of metal, with turned-over edges notched at their bends, and then insert a card, or it would even be possible to bend the metal body in the shape shown in Fig. XI, so as to form two channels, into which two cards could be inserted, one carrying the names and the other designations, either or both of which are therefore changeable, as desired. It is not intended to limit the scope of this patent to the exact shapes, sizes, proportions, or materials of parts, and the patent clearly does not limit the use of the invention to laundry-cards or designations by way of numbers for the reasons above explained. To this end the claims below are intended to cover the broadest construction consistent with the intent of this specification.
- What is claimed as new is—
1. A designator comprising a body having series of notches in opposed edges, names adjacent one series, designations adjacent an opposed series, and an indicator leading from a notch opposite a name to a notch opposite a designation. 105
  2. A designator comprising a body having series of notches in opposed edges, names adjacent one series, designations adjacent an opposed series, and a flexible indicator attached to the body and leading thence around it, first through a notch opposite a name, then through a notch opposite a designation which it is desired to connect with that name, then behind the body, and so on. 115
  3. A designator comprising a body having series of notches in opposed edges, names adjacent one series, designations adjacent an opposed series, a flexible indicator leading through a name-notch, thence through a designation-notch, and so on, and a fastening device to which the indicator is finally attached. 125
  4. A designator comprising a body having series of notches in opposed edges, names adjacent one series, designations adjacent an opposed series, a flexible indicator leading through a name-notch, thence through a des- 130

ignation-notch, and so on, and a fastening device consisting of a slit in the body through which the indicator is finally drawn.

5. A designator comprising a body having 5 series of notches in opposed edges, names adjacent one series, designations adjacent an opposed series, a flexible indicator leading through a name-notch, thence through a designation-notch, and so on, and a fastening device 10 consisting of a slit formed in the body at the bottom of a notch through which the indicator is finally drawn.

6. A designator comprising a body having 15 series of notches with words adjacent them, a flexible indicator adapted to be wound around the body through certain notches, and a fastening device consisting of a series of notches with a slit at the bottom of each notch, words also being printed opposite these notches.

20 7. In a designator comprising a body and a flexible indicator substantially as described, a combined designation and fastening device consisting of a series of slits cut in the edge of the body and into which the indicator may 25 be drawn, and words opposite said slits.

8. In a designator comprising a body and a flexible indicator substantially as described, a combined designation and fastening device 30 consisting of a series of notches in the edge of the body with a slit at the bottom of each notch for the purpose set forth, and words opposite said slits.

9. As a new article of manufacture, a laundry-counter or the like comprising a body 35 having series of notches along its opposed edges, names of articles of wash opposite one series, abstract numerals opposite the other series, price-numerals respectively opposite the names, a flexible indicator adapted to connect the notches in pairs as described, and means for holding the indicator in place.

10. A designator comprising a body having 40 series of notches in opposed edges, names adjacent one series, designations adjacent an opposed series, a flexible indicator leading through a name-notch, thence through a designation-notch, and so on, and a fastening device 45 consisting of a series of slits through one of which the indicator is finally drawn, these slits themselves having designations marked opposite thereto.

50 11. An enumerator or designator comprising

ing a rectangular body having notches along its side edges and a series of slits along one end, names adjacent one series of notches, 55 numerals adjacent the opposite series of notches, designations adjacent the slits, an eyelet near the upper end of the body, and a cord tied near one end into said eyelet, as and for the purpose set forth.

60 12. An enumerator or designator comprising a rectangular body having notches along its side edges and one end and a series of slits along the other end, names adjacent one series of side notches, numerals adjacent the 65 opposite series of notches, designations adjacent the end notches and the slits, and a cord tied near one end to the body, as and for the purpose set forth.

70 13. A designator comprising a body having 75 series of notches in opposed edges, with series of words opposite each series of notches, and an elastic indicator adapted to be led from a notch of one series to a notch of another.

75 14. A designator comprising a body having series of notches in opposed edges, with series of words opposite each series of notches, and a plurality of flexible indicators of different color, each adapted to lead from a notch 80 in one series to a notch in another, and each capable of use independently of the other.

85 15. A designator comprising a comparatively delicate body with names in series along opposed edges thereof, comparatively strong clamps covering said edges and themselves 90 provided with notches opposite the names, and an indicator adapted to lead from a notch at one edge to a notch at the other.

90 16. A designator comprising a flat body, 95 clamps along its opposed edges and provided with outwardly-facing notches, strips held by the clamps against the body and marked with series of words spaced to stand opposite said notches, and an indicator adapted to lead from a notch at one edge to a notch at the other.

In testimony whereof we affix our signatures in presence of two witnesses.
